UNITED STATES PATENT OFFICE.

EMORY GLENN SIMPSON, OF DETROIT, MICHIGAN, ASSIGNOR TO FISHER BODY CORPORATION, OF DETROIT, MICHIGAN, A CORPORATION OF NEW YORK.

DOOR-LOCK.

1,401,369.

Specification of Letters Patent. Patented Dec. 27, 1921.

Application filed January 22, 1920. Serial No. 353,213.

To all whom it may concern:

Be it known that I, EMORY GLENN SIMPSON, a citizen of the United States, residing at Detroit, in the county of Wayne and State of Michigan, have invented certain new and useful Improvements in Door-Locks, of which the following is a specification.

This invention relates to automobile door locks and has for its object a lock which has not only the ordinary features of an automobile door lock but which also has a pin tumbler or cylinder lock that can be set with the key from the outside of the door to lock the door from opening from the outside.

The lock in no way affects the inside lever handle which may be manipulated whether the lock is on or off. In fact, the lock is, in operation, very similar to the ordinary night lock on a house door but the parts that accomplish the locking action are differently arranged than the ordinary night lock and the lock is set in the on or off position simply by the use of the cylinder key.

On all but one door of a closed car a similar lock is used set in locked position by a button.

In the drawings,—

Figure 1 is a rear elevation of the detached lock showing the locking dog set to prevent the operation of the outside handle.

Fig. 2 is a similar view showing how notwithstanding the position of the locking dog it in no way affects the inside handle which is in the course of operation.

Fig. 3 is a similar view showing the locking dog turned to a position of non-interference with the outside door handle retractor. In this position the door may be opened freely from the inside or outside.

Fig. 4 is a section taken on the line 4—4 of Fig. 1 and showing the lock mounted on the door.

Fig. 5 is a detail in perspective of the locking dog.

Fig. 6 is a detail in perspective of the outside retractor.

Fig. 7 is a detail in perspective of the finger and disk by which the locking dog is operated.

Fig. 8 is a cross-section showing a modified form of lock which can be used on the other doors of a closed body.

Fig. 9 is an elevation of a sedan showing the key lock on one door and the button lock on the remaining door.

a designates the lock housing which is of ordinary form comprising a face plate and a front plate. *b* is the rear plate that completes the lock housing. *c* is a sliding bolt guided through the face plate and between the rear plate *b* and the upstanding lugs *d* of the front plate. The sliding bolt *c* is provided with two lugs *e* and *f*. The lug *e* is adapted to be engaged by the inside lever *g* and the lug *f* by the retractor *h* which is connected with the spindle *i* that is attached to the outside door handle *j* that may be secured to the door frame by the escutcheon *k*. *l* is a torsional spring adapted to bear against a shoulder in the sliding bolt and tends to project the sliding bolt outwardly as shown in Fig. 1. This forces the inside lever *g* up against the stop *m*. This much of the construction is a conventional lock construction now in use in automobile body construction.

The improvement consists in the locking devices by which the sliding bolt may be locked against retraction by the turning of the outside handle. This is accomplished by the use of the locking dog *n* detailed in Fig. 5 which has a turned-up lip *o* adapted to be engaged by the finger *q* (Fig. 7) on the rotating disk *r* which is rotatably supported in the front plate of the housing *a* by turning over the edges *s* of the hub portion.

The aperture through the hub portion is square and adapted to take the squared reduced end *t* of the extension spindle *u* secured to the end of the barrel of the cylinder or pin tumbler lock *v*. It is well known that a key of the cylinder or pin tumbler type of lock requires to be turned through a complete revolution before it can be withdrawn. Ordinarily the key only turns one way and is turned for the purpose of retracting the sliding bolt. Here the purpose of the cylinder lock and key is simply to turn the locking dog *n* to a position of interference with the retractor *h* as shown in Figs. 1 and 2, or to a position of non-interference with the retractor *h* as shown in Fig. 3. This is done by turning the cylinder key in one direction or the other through a complete turn. For instance, if it is desired to set the lock on the outside handle, from the position of the

locking dog *n* to a position of interference with the retractor *h*, the key is turned through a complete revolution in one direction, as shown in Fig. 1, so that the locking dog *n* is turned to a position of interference with the retractor *h*.

When the key is turned through a complete revolution in the opposite direction, as shown in Fig. 2, the locking dog *n* is turned to a position of non-interference with the retractor *h*.

When the key is turned through a complete revolution in one direction, as shown in Fig. 3, the locking dog *n* is turned to a position of non-interference with the retractor *h*.

When the key is turned through a complete revolution in the opposite direction, as shown in Fig. 4, the locking dog *n* is turned to a position of interference with the retractor *h*.

When the key is turned through a complete revolution in one direction, as shown in Fig. 5, the locking dog *n* is turned to a position of interference with the retractor *h*.

parts as shown in Fig. 3, the disk r is turned clockwise, when viewed from the position shown in Fig. 3, while the key, considered from the outside of the door, 5 would be turned counter-clockwise. This would bring the parts to the position shown in Fig. 1 after a complete turn has been made. The key may then be withdrawn. The locking dog obviously has no effect on 10 the inside handle, as is clearly shown in Fig. 2, where the inside handle is being actuated.

The great advantage of this lock is that the owner can always keep the lock on his 15 closed car door and all he has to do is simply leave the car and slam the door shut, and if at any time he desires to take the lock "off," all he has to do is to insert and turn his cylinder key.

20 The lock as described could, of course, be placed upon all the doors of a closed car, but it is preferable to omit the cylinder lock on all but one door and operate the disk r simply with a button x on the inside of 25 the door, as shown in Figs. 8 and 9. Hence any door can be used for egress but only one can be unlocked from the outside.

What I claim is:

1. In a lock, the combination of a housing 30 having parallel front and rear plates, a bolt slidable in said housing, an inside lever for independently retracting said bolt, an outside spindle provided with a retractor for retracting the bolt independently of 35 the inside lever, a dog pivoted to the inside of one of the above mentioned housing plates, the said dog having a portion swinging in the same plane as the outside spindle retractor and having the swinging arcs of 40 the dog and retractor intercepting, the dog capable of being set to prevent operation

of the retractor, but permitting the retraction of the bolt by the inside lever and also by the shutting of the door, a disk pivoted to the plate carrying the dog, a cylinder 45 lock for insertion in the outside of the door, a connecting spindle from the lock cylinder having a detachable but rotatable connection with the said disk, and a connection between the disk and dog involving 50 lost motion to permit the extraction of the key from the lock but serving to actuate the dog to turn it from position of interference with the retractor to position of clearance or vice versa. 55

2. In a lock, the combination of a housing having parallel front and rear plates, a bolt slidable in said housing, an inside lever for independently retracting said bolt, an outside spindle provided with a retractor 60 for retracting the bolt independently of the inside lever, a dog pivoted to the inside of one of the above mentioned housing plates, the said dog having a portion swinging in the same plane as the outside spindle 65 retractor and having the swinging arcs of the dog and retractor intersecting, the dog being capable of being set to prevent operation of the retractor but permitting the retraction of the bolt by the inside lever and 70 also by the shutting of the door, a disk provided with a finger and pivoted to the plate carrying the dog, a cylinder lock for insertion in the outside of the door, and an actuating connection between the finger of 75 the disk and the dog permitting the finger to rotate through a large part of a turn in lost motion to permit withdrawal of the key.

In testimony whereof I affix my signature.

EMORY GLENN SIMPSON.
